W. STORCK

GRINDING DEVICE

Filed June 2, 1925

FIG. 1.

FIG. 2.

FIG. 3.

Inventor:
Walter Storck
by *Refidur*

Atty.

UNITED STATES PATENT OFFICE.

WALTER STORCK, OF BERLIN, GERMANY.

GRINDING DEVICE.

Application filed June 2, 1925, Serial No. 34,352, and in Germany September 25, 1924.

When grinding a work-piece circularly it is carried preferably between dead or fixed centres in order to render ineffective eventual untrue running of the dead centres. The 5 work-piece is rotated in such cases by the intermediary of a driving disk rotating upon a stationary pivot.

Internal grinding cannot, unfortunately, be effected in the same manner because the 10 supporting pivot for the above mentioned driving disk can be only comparatively short, and cannot, therefore, counteract sufficiently the weight of the work-piece it is to carry. The supporting members would 15 inevitably be worn off and the internal grinding would be unsatisfactory.

In connection with the driving of machines by overhead countershafts, or overhead transmission gears respectively, devices 20 have become known rendering possible alternate grinding between a dead centre and a rotating tool spindle. With machines of this kind the head stock or mandrel stock is provided with two pulleys, of which one 25 is keyed to the shaft, whereas the other is so devised as to be able to serve also as driving disk, and rotates loosely upon the work-piece spindle, which may be rendered stationary, if desired, by means of a pin. 30 When grinding between dead centres the driving belt is laid upon said other pulley and rotates the work-piece spindle, which carries on one of its ends the chuck provided for the reception of the work-piece.

With circular grinding machines, which are operated singly by means of a shaft located in most cases in the interior of the machine, and which do not require, therefore, an overhead counter-shaft gearing which 35 can thus be dispensed with, arrangements and combinations of parts of the above-stated kind cannot be used. Instead thereof the new arrangement and combination of parts constituting the present invention is 40 presented which consists of a headstock in which are supported two shafts which are equidistant from a vertical axle. By reason of this arrangement either the driving gear for the dead centres or the driving gear for 45 the bearing chuck may be turned towards the grinding disk without necessitating the

actuation of any change-over mechanism or member.

My invention is illustrated diagrammatically and by way of example on the accompanying drawing in which Figure 1 is a side-view of the improved grinding device, partly in vertical section; Figure 2 is a plan thereof, in horizontal section, and Figure 3 is a frontal view, seen lefthand with respect to Fig. 1.

The driving gear for the head stock, which is common for both kinds of use, is actuated by means of a shaft 1, a bevel-wheel 2 affixed thereto, a bevel-wheel 3 meshing with the wheel 2, a shaft 4 to which the bevel-wheel 3 is affixed, a bevel-wheel 5 secured to the shaft 4, a bevel-wheel 6 meshing with the wheel 5 and being firmly connected with a spur wheel 7, these two wheels (6 and 7) being affixed to a shaft 8. The wheel 7 rotates a spur-wheel 9 keyed to a sleeve 10 to which are keyed a plurality of other spur-wheels of different diameters, as shown in Fig. 2, by which the rotary speed can be reduced. These wheels serve for operating a draw-key gear which does not form part of this invention and is, therefore, not described in detail in this specification. The draw-gear serves for rotating the shaft 12 whereby the means for interior grinding are provided. The other end of the shaft 12 carries a spur-wheel 13 firmly connected therewith and meshing with another spur-wheel or worm wheel 14 which is so devised as to be adapted to serve also as a driver disk. The stationary centre 15 is located in the non-rotary spindle 16.

In order to change the manner of driving the headstock the three screws or bolts 17 shown in Figs. 2 and 3 are loosened and the headstock is turned around the shaft 4 so as to change the position of the parts concerned relatively to the grinding disk carrier as desired.

I claim:

1. In a machine tool, a headstock comprising a rotatable casing mounted on the frame of the tool, a fixed shaft mounted on the casing and carrying a dead centre, a rotatable shaft mounted on the casing and carrying a chuck, and means permitting ro-

tation of said casing on the frame of the tool for presenting either the dead center shaft or the chuck carrying shaft to the work.

5. 2. In the combination specified in claim 1, the fixed and rotatable shafts being parallel with each other and mounted on opposite sides of said casing.

3. In the combination specified in claim 1, a driving disk mounted on said fixed shaft, and means for rotating said driving disk.

In testimony whereof I have affixed my signature.

WALTER STORCK.
